UNITED STATES PATENT OFFICE.

MARY JORDAN SMITH, OF NEW YORK, N. Y.

DESIGN FOR A PIN.

SPECIFICATION forming part of Design No. 31,065, dated June 27, 1899.

Application filed June 2, 1899. Serial No. 719,154. Term of patent 14 years.

To all whom it may concern:

Be it known that I, MARY JORDAN SMITH, a citizen of the United States, residing at the city of New York, borough of Manhattan, in 5 the county and State of New York, have invented and produced a new and original Design for a Pin, of which the following is a specification, reference being had to the accompanying drawings, forming a part thereof, 10 in which—

Figure 1 is a perspective view of a pin embodying the features of my design, and Fig. 2 is a side elevation of the same.

The design relates to that class of pins 15 adapted to attach dress-shields to garments or for analogous uses.

The leading feature of the design consists in a foundation-plate in which an irregular opening appears and a tongue which extends 20 over the face of the foundation-plate and across the opening therein.

The minor feature of the design consists

in locating the opening B near one end of the foundation-plate A, which is oblong. The irregularity of the opening B is due to a recess C appearing in the outer end wall, together with an extension D, that projects from the inner end wall of the opening B at an inclination longitudinally of the recessed wall of said opening. A tongue E rises from 25 one end of the foundation-plate A and is of tapering form, extending longitudinally of the plate across the opening B at that side opposite which the extension D is located, and spur projections F appear at intervals 30 upon the foundation-plate A.

I claim—

The design for a pin herein shown and described.

MARY JORDAN SMITH.
